UNITED STATES PATENT OFFICE.

ELI EPSTEIN, OF STAMFORD, CONNECTICUT, ASSIGNOR TO THE YALE & TOWNE MANUFACTURING COMPANY, OF STAMFORD, CONNECTICUT.

LOCK MECHANISM.

Application filed December 16, 1922. Serial No. 607,340.

To all whom it may concern:

Be it known that I, ELI EPSTEIN, a citizen of the United States, and a resident of Stamford, in the county of Fairfield and 5 State of Connecticut, have invented certain new and useful Improvements in Lock Mechanism; and I do hereby declare the following to be a full, clear, and exact description of the invention, such as will enable 10 others skilled in the art to which it appertains to make and use the same.

This invention relates to improvements in lock mechanism and more particularly to such as embody cylinder lock mechanism,— 15 one object of the invention being to provide a cylinder lock which shall be non-pickable.

A further object is to so construct a cylinder lock that pin tumblers such as heretofore commonly employed in cylinder locks 20 shall be displaced by tumblers of a different construction and which cannot be set to unlocking positions with the use of a picking tool of any type, and to so construct the mechanism that the tumblers may readily 25 be made adaptable for operation with the use of a "master" key if desired, and so that the tumblers may be made interchangeable so that they may be arranged for operation by a specially made key for each lock.

30 A further object is to so construct a cylinder lock embodying rotatable disk tumblers, that keys of the type heretofore employed in the operation of pin-tumbler locks may be utilized.

35 With these and other objects in view, the invention consists in certain novel features of construction and combinations of parts as hereinafter set forth and pointed out in the claims.

40 In the accompanying drawings;

Figure 1 is a view of a mortise lock (with the cover plate removed) showing an application of my invention;

45 Figure 2 is an enlarged sectional view of the cylinder lock mechanism;

Figure 3 is a sectional view (with the tumblers in elevation) on the line 3—3 of Figure 4;

50 Figure 4 is an inner end view of the cylinder lock, showing the devices which cooperate with the bolt and latch mechanism of the mortise lock shown in Figure 1;

Figure 5 is a view in transverse section on the line 5—5 of Figure 2;

55 Figure 6 is a transverse sectional view on

the line 6—6 of Figure 2, showing the parts in locking position;

Figure 7 is a section on the line 7—7 of Figure 2;

Figure 8 is a sectional view similar to 60 Figure 6 showing the parts in unlocking position;

Figure 9 is a detail view of the sleeve 19;

Figure 10 is a perspective view of the fence, 65

Figure 11 is a detail view of the head piece for the inner end of the fence-carrying sleeve, and

Figure 12 is a sectional view showing the forward positions of the tumbler structure 70 and fence carrier.

In Figure 1 of the drawings, I have shown the application of my improvements to a mortise lock which, in the embodiment here shown, comprises a casing 1 having bolt and latch mechanism mounted therein, said mechanism including a bolt member 2 and a latch member 3. As here shown, the bolt is provided with a talon 4, and a tumbler 5 with which the operating member of the cylinder lock cooperates. The latch 3 is normally pressed forwardly by a spring 6 and the spindle 7 of the latch is provided with a head 8 with which the knob-operated mechanism shown at 9 cooperates. A spring-pressed lever 10 is pivoted to the bolt member 2 and provided at its free end with lateral arms 11 and 12. A bell-crank 13 is pivotally mounted intermediate of the bolt and latch members,—one arm 14 of said bell-crank being adapted to cooperate with the head 8 on the latch spindle and the other arm of said bell-crank provides a cam 15 engaged by the arm 12 of the lever 10,—the arm 11 of said lever being adapted to be engaged by the operating device actuated by the cylinder lock mechanism, as more fully hereinafter explained.

My improved cylinder lock mechanism includes a shell or casing 16 to pass through 100 a suitable opening in a door as is customary with the application of cylinder locks and a portion of said shell or casing may be threaded, as at 17 to be screwed through a suitable opening in the lock casing 1, and held in fixed position by a bolt 18 as clearly shown in Figure 1. The main casing 16 contains a sleeve 19 which is fixed within said casing by screw 20 as shown in Figure 2,—said screw being projected beyond the 110

end of the casing 16 and sleeve 19 to form a pin 21 for a purpose hereinafter explained. The interior fixed sleeve 19 is provided with a slot 22 to receive a fence 23, and in said slot, a light spring 24 is located to bear against said fence. A revoluble key plate 25 carries a centrally located post 26, and a plurality of disk tumblers 27 are mounted to rotate about said post,—said tumblers 10 being separated from each other by spacers 28 and said tumblers and spacers are provided with gatings 29 and 30 respectively for the reception of the fence. A tube 31 passes through holes located centrally in the tumblers and spacers and said tube is mounted on the post 26. The tumblers and spacers are located between end plates 32 and 33 on the tube 31,—the plate 33 having central wrench receiving enlargement 34 on the inner end of said tube and a headed screw 35 enters the inner end of the post 26. The spacers 28 of the tumbler mechanism are prevented from turning by means of a pin 36 which passes through them at one side 25 of their axes,—said pin being made fast at one end to the end plate 33 and projecting at its front end into a socket 37 in the key plate 25. The pin also passes through segmental slots 38 with which the several tumblers 27 are provided. Springs 39 are located in the slots 38 of the tumblers and each of said springs bears at one end against one end of the slot in which it is located and at the other end against the pin 36,—said 30 springs 39 thus acting normally to so turn the tumblers as to cause their gatings to stand out of line with each other and out of line with the gatings of the spacers. The several tumblers are provided with key slots 40 to receive a key passed through the key slot 41 in the key plate 25 and the spacers are also provided with suitable key slots which normally align with the key slot in the key plate 25. The key slots in the tumblers are so shaped and proportioned that when a proper key (which latter may have a construction similar to keys used with pin-tumbler locks) is inserted and caused to pass through them, said tumblers will be rotated, 45 against the resistance of the springs 39, to such relative degrees that the gatings of the several tumblers will be brought into alignment with each other and with the gatings of the spacers, to receive the fence 23, which latter will be caused to enter said gatings by the action of the light spring 24.

The fence 23 is mounted in a slot 42 (open at one end 42^a) in a cylindrical carrier 43 disposed loosely within the fixed shell sleeve 19 and in a manner to surround the stacked tumbler structure. The fence 23 is beveled at its respective ends as indicated at 23^a and 23^b and the inner end of the slot 42 may be beveled as shown in Figure 3. The stacked tumbler structure and fence carrier are so

mounted that they are capable of limited endwise movement and the beveled ends of the fence are cooperable, respectively, with a beveled peripheral portion 44 of the key plate 25 and a beveled face 45 on the peripheral portion of the end plate 33 of the tumbler structure. 70

Normally, the fence 23 will be disposed, partly in the slot 42 of the carrier 43 and partly in the slot 22 in the fixed lining sleeve 19, so that the fence carrier will be locked against rotation. A head 46 is mounted in the inner end of the sleeve or fence carrier 43 and prevented from turning relatively thereto by flanges 47 projecting from said head entering suitable notches in the end of the sleeve or carrier. The head 46 is also secured to the sleeve or carrier by set screws, as indicated at 47^a. 75

Because of the fact that the key plug of 85 the mechanism is concentric with the cylinder, (instead of eccentric to the axis of the cylinder as in pin tumbler locks), the cam devices whereby motion is imparted from the plug structure (which latter includes the 90 tumbler structure and the fence carrier) comprise relatively movable parts 48 and 49,—the part 48 constituting a guide for the part 49 which is cooperable with the talon of the bolt member 2. The guide member 95 48 of the cam devices is pivotally mounted near one end on the pin 21 carried by the casing of the cylinder lock and said member 48 is provided with an elongated slot 50 for the accommodation of a screw 51 and its 100 bushing 52, whereby the member 49 is pivotally connected eccentrically with the head 46 of the fence sleeve or carrier 43. By thus constructing the cam device, rotation of the sleeve or carrier 43 and its head 105 46, will cause the guide member 48 to oscillate and the member 49 to reciprocate relatively to the member 48 and (when projected) to mark the arc of a circle which will intersect the talon of the bolt and effect 110 the retracting or the projecting of the same. 115

When a proper key is inserted through the tumblers of the cylinder lock so as to bring their gatings into alignment, the tumbler structure and fence carrier will be moved longitudinally to the positions shown in Figure 12 and to an extent sufficient to permit the fence to enter the gatings of the tumblers (when said gatings and fence are brought into alignment), the spring 24 serving to press the fence into the gatings. When the fence is thus moved into the gatings of the tumblers, it will move out of the slot 22 in the fixed cylinder or casing sleeve 19 (thus unlocking the fence carrier 43 from the casing), and lock the tumblers to the fence carrier, so that when the key is then turned, the tumbler structure and the fence sleeve or carrier will be rotated together and motion imparted to the cam de- 120 125

vices 48—49 to effect operation of the bolt structure 2 as previously explained.

When the key is withdrawn from the lock, the tumbler structure and fence carrier will be given a slight forward longitudinal movement, causing the beveled face 45 on the head 33 and the bevel 44 on the key plate 25 respectively, to so co-act with the beveled ends of the fence 23 as to force the latter out 10 of the gatings of the tumbler structure and into the slot 22 in the fixed lining sleeve 19, thus releasing the tumbler structure and locking the fence carrier to the casing. The parts will then be in their normal position, 15 with the fence carrier and the cam devices connected therewith, locked against movement and the tumbler structure free to rotate. It will be seen that should an 20 improper key be inserted into the lock so that the gatings would not be brought into alignment, the turning of such key would merely result in the free turning of the tumbler structure and no motion would be 25 imparted to the fence carrier nor to the cam devices.

When a proper key is inserted into the lock and turned, the sweep of the cam devices 48—49 will cause the member 49 thereof to depress the tumbler 5 and then engage 30 the talon 4 and withdraw the bolt 2. The key may then be again turned to cause the cam devices to make another sweep in the same direction as before, and the arm 11 of the lever 10 being now within the path 35 of the cam-member 49 it will be engaged by said cam member, and the lever 10 will be moved sidewise and caused, through the medium of the bell-crank 13, head 8 and spindle 9 to effect retracting of the latch 3.

40 My improved cylinder lock may readily be made adaptable for use of a master key by simply providing additional gatings in the disk tumblers to align with the fence, and the combination of the tumblers may be 45 changed to accommodate them for cooperation with the bitings of the particular key which it may be desired to employ with a particular lock.

Various changes might be made in the 50 details of construction of my invention without departing from the spirit of the latter or limiting its scope and hence I do not wish to restrict myself to the precise details herein set forth.

55 Having fully described my invention what I claim as new and desire to secure by Letters-Patent, is:—

1. In a lock mechanism, the combination 60 with bolt mechanism, of a cylinder lock comprising a cylindrical casing and key controlled mechanism rotatable therein and having its axis of rotation coincident with the axis of said cylindrical casing, and cam devices comprising relatively movable and 65 cooperable members, one of said members

pivoted to said casing and the other member pivotally connected with the rotatable key controlled mechanism.

2. In a lock mechanism, the combination 70 with bolt and latch mechanism, of cylinder lock mechanism comprising a casing and a rotatable key controlled mechanism, and cam devices comprising relatively movable and cooperable members, one of said members pivoted to said casing and the other 75 member pivotally connected with the rotatable key controlled mechanism, whereby when said last-mentioned mechanism is given successive rotation, the sweep of the cam devices will cooperate with the bolt mechanism to withdraw the bolt and subsequently with the latch mechanism to withdraw the latch.

3. In lock mechanism, the combination 80 with bolt mechanism including a talon and a tumbler, latch mechanism including a lever pivotally connected with the bolt-mechanism and connections between said lever and the latch of the latch mechanism, of a cylinder lock comprising a casing and a rotatable key-controlled mechanism and cam devices including relatively movable and cooperable members, one of said members pivotally connected with the casing and the other member having eccentric pivotal connection with the rotatable key controlled mechanism, whereby when said last-mentioned mechanism is rotated, one of said 90 cam members will depress the tumbler and engage the talon of the bolt mechanism to 95 withdraw the bolt and whereby when said key controlled mechanism is again rotated in the same direction, said cam devices will engage said lever and effect retracting of the latch.

4. In lock mechanism, the combination 100 with a casing and rotatable key-controlled mechanism mounted therein so as to be coaxial with said casing, of cam devices comprising relatively movable cooperable members, one of said members constituting a 105 guide for the other and having an elongated slot, the guide member pivotally connected with the casing, and means extending through said elongated slot and pivotally 110 connecting the other member eccentrically with the rotatable key-controlled mechanism.

5. In lock mechanism, the combination 115 with a casing, of disk key controlled tumbler mechanism normally freely rotatable within the casing, a rotatable member, a fence normally locking said rotatable member to the casing, and means to cause said fence to enter aligned gatings of the disk tumblers 120 and simultaneously unlock said rotatable member from the casing and lock it to the tumblers so that said rotatable member and tumbler mechanism may be rotated together 125 by manipulation of the key.

6. In lock mechanism, the combination with a casing, of key controlled disk tumbler mechanism coaxially mounted in said casing and normally free to turn, a rotatable member interposed between said tumbler mechanism and the casing, a fence carried by said rotatable member and normally locking the same to the casing, means pressing said fence toward the tumbler mechanism and adapted to move said fence out of locked engagement with the casing and into aligned gatings of the tumblers, and means whereby the fence will be moved out of the gatings of the tumblers and into locked engagement with the casing during withdrawal of a key from the tumbler mechanism.

7. In lock mechanism, the combination with a casing, of key-controlled disk tumbler mechanism coaxially mounted in said casing and normally free to turn, said tumbler mechanism being capable of limited longitudinal movement, a rotatable member interposed between the tumbler mechanism and the casing, a spring pressed fence carried by said rotatable member for cooperation with the tumbler mechanism and normally in locked engagement with the casing, and means operable by longitudinal movement of the tumbler mechanism to move the fence out of engagement with the tumbler mechanism and into locked relation to the casing and to permit the fence to be pressed out of locked relation to the casing and into the gatings of the tumbler mechanism.

8. In lock mechanism, the combination with a casing, of key controlled disk tumbler mechanism co-axially mounted in said casing and normally free to turn, a rotatable member interposed between said tumbler

mechanism and casing and having a slot, said tumbler mechanism and rotatable member mounted to have limited longitudinal movement, a spring-pressed fence located in the slot in said rotatable member and normally in locked relation to the casing, said fence having beveled ends, said casing carrying a beveled part cooperable with one beveled end of the fence and the tumbler mechanism carrying a part movable therewith and having a beveled face to cooperate with the other beveled end of the fence.

9. In lock mechanism, the combination with a casing, a rotatable member therein, and a fence carried by said rotatable member and having normal locked relation to the casing to lock said rotatable member, of disk tumbler mechanism mounted coaxially within said rotatable member, said tumbler mechanism including a plurality of disk tumblers, means whereby said tumblers are axially mounted, each disk tumbler having a key opening at one side of its center and also having a segmental slot, a pin passing through the segmental slots of the tumblers, and a spring located in the segmental slot of each tumbler and bearing at one end against one end of said slot and at the other end against said pin, and means whereby said fence carried by the rotatable member may be caused to move out of locked relation to the tumblers and into locked relation to the casing and vice versa.

In testimony whereof, I have signed this specification in the presence of two subscribers.

ELI EPSTEIN.
